UNITED STATES PATENT OFFICE.

JESSE I. ANDERSON, OF INDIANAPOLIS, INDIANA, ASSIGNOR TO J. I. HOLCOMB MFG. COMPANY, OF INDIANAPOLIS, INDIANA, A CORPORATION.

MOP.

Application filed September 26, 1927. Serial No. 221,945.

This invention relates to a mop for dusting, cleaning or the like.

One of the chief objects of the invention is to provide a mop which is not only adaptable 5 for hand manipulation but which is adapted to receive a head and securely mount the same without the use of any subsequent fastening.

The chief feature of the invention consists 10 in the formation of a mop body and a mop head frame having cooperating parts arranged to accomplish the foregoing object.

Another feature of the invention consists 15 in the inherent resiliency in the connection between the handle and the frame or head.

The full nature of the invention will be understood from the accompanying drawings and the following description and claims.

In the drawings Fig. 1 is a perspective view 20 of a mop body, frame and handle in assembled relation, the dotted lines indicating a position assumed in connecting the same. Fig. 2 is a longitudinal central sectional view thru the same. Fig. 3 is a vertical sectional view 25 of the resilient or yielding connection between the handle and the frame. Fig. 4 is a similar view of the same parts shown in Fig. 3 but in a different position. Fig. 5 is a view similar to Figs. 3 and 4 but with the part in a 30 still different position.

This invention is an improvement upon that shown in a copending application Serial No. 161,795, filed January 18, 1927, in that the mop body or swab is more adaptable for 35 hand manipulation if and when desired independent of the employment of a frame or head and is a continuation of the aforesaid application in that the copending application, as shown in Fig. 3, illustrates the resilient connection between the handle and the frame.

The mop body includes a pair of substantially similar elongated, and herein said iron shaped, imperforate fabrics 10 and 11, the upper fabric 10 and the lower fabric 11 being 45 united along their periphery by a tape 12 which merely assists in securing a better sewing. This forms a pocket 13 between the two fabrics, the lower fabric supporting the swab or tufted body portion 14. The rear 50 end of the mop body is substantially open except for a short distance extending inwardly from each of the elongated sides as at 15. The top fabric, if desired, may be relieved by the curved cut out portion 16, 55 although the same is not necessary. In ad-

dition to the sewing together of the rear portions of the fabrics for a short distance inwardly from the elongated edges as indicated at 15, the eyelets 17 or other permanent metallic fasteners may be employed or the same may be substituted for said sewing. The resultant construction, therefore, is a mop body which is adapted to receive the operator's hand and be useful as a swab or duster when hand operation is desired. 65

The frame or head includes a wire 18 having substantially the same peripheral outline as the mop head with inward extensions 19 at the rear end and the inward extensions extend forwardly and outwardly and in diverging relation forming arms 20, each of which has an inward extension 21 that lies parallel with the other and adjacent thereto, as shown in the several figures. 70

All of the aforesaid portions of the mop 75 head or frame lie in substantially the same plane and the two sides are brought together, the same being permitted by an inherent resiliency of the construction, as shown by the dotted lines at A in Fig. 1 so as to pass thru 80 the slightly restricted end opening of the mop body. After passing thru said opening, as shown by the full lines in Fig. 1, the frame expands and seats itself in the pocket of the mop head with the lateral portion 19 anchored 85 at the corners against longitudinal displacement by either the eyelets 17 or the equivalent sewing 15. The handle supporting portion of the frame 18 overlies the top fabric 10 and bears down upon the same in clamping relation 90 which further prevents separation of the mop body and the frame.

A handle 30 has its lower end suitably secured to a hinge member having a portion in the form of a socket 31 by a screw thread 95 connection 32 or by other equivalent means and said screw thread socket 31 is formed as a continuation of the strip of metal 33, the opposite end of which is doubled upon itself to form a loop 34, the doubled portion being 100 secured to the body portion as at 35. The loop 34 receives the two parallel abutting ends 21 of the spring frame and Figs. 1 and 2 show the normal positioning of the several frame ends and the loop connection. When 105 the parts are positioned as shown in Fig. 3 one of the arms 20 is moved rearwardly and the other one is moved forwardly, thereby placing a tension upon the frame which if released, normally tends to return the mop 110

to the position shown in Figs. 1 and 2. Similarly, when the two ends 21 are positioned substantially transverse to the plane of the frame the two arms are in approximately 5 normal position. When the parts are reversely positioned, as shown in Fig. 5, reference being had to Fig. 3, the handle again lies parallel to the frame but extends forwardly thereof instead of rearwardly and 10 the handle is subjected to opposite tension which tends to return the same to the position shown in Figs. 1 and 2.

The invention claimed is:

1. A "slip-in" type mop wire frame comprising a substantially semi-elliptically arranged wire including inwardly extending rear ends terminating short of each other with laterally and inwardly extending projections terminating in angularly and inwardly extending ends positionable adjacent each other within the confines of the frame, all of said frame portions lying in substantially the same plane.

2. A mop frame including a single wire arranged in semi-elliptical outline with the point and side portions immediate continuations of each other, the rear ends of the sides extending inwardly therefrom and towards each other but terminating short of meeting engagement, lateral extensions therefrom each extending forwardly and towards the immediately adjacent side, and an end of the wire constituting a lateral extension of each of the last mentioned extensions and extending toward the opposite side and lying adjacent the similarly and oppositely directed end and constituting a single pivot substantially in the plane of the elliptical frame for pivotal support of the same.

3. In a mop, a mop body including a pair of elongated similar fabric members secured together at their peripheral edges with their rear ends normally unsecured except for a short distance immediately adjacent the 45 corners for forming a pouch with an open rear end of slightly less width than the width of the pouch, a pouch supporting wire frame including a peripheral portion substantially conforming to the outline of the pouch and

slidably receivable thereby through the open rear end thereof and normally laterally expandable for seating in said pouch and retainable therein by the restrictions of said opening at the rear end of the pouch, said wire frame including a handle supporting portion extending inwardly and forwardly and lying above the pouch intermediate the front and rear thereof when positioned therein for mounting a handle within the pouch outline, and a handle for connection to the inwardly and forwardly over-lying portion of the wire frame.

4. In a mop having a handle and a mop head, the combination of a single wire spring frame having an intermediate body portion mounting said mop head and a pair of free ends arranged to lie adjacent each other for forming a single pivot, the axis of which lies parallel to said ends, and a metal strip having one end forming a ferrule for receiving the end of the handle, the other end of said metal strip being doubled back upon itself but terminating short of the ferrule and being secured in closed tubular formation with its axis transverse to the ferrule axis for receiving said pivot.

5. A "slip-in" type mop frame comprising a substantially semi-elliptical framework including inwardly extending rear ends terminating short of each other with laterally and inwardly extending projections terminating in angularly and inwardly extending ends positionable adjacent each other intermediate the ends of the frame, all of said frame portions lying in substantially the same plane, a handle and a connecting portion between said handle and said parallel ends including a loop for simultaneously receiving both ends, said loop being elongated and arranged to roll one of the ends upon the other in the turning movement of the handle for angular positioning relative to the plane of the frame, thereby imparting tension to the frame and handle connection for returning the handle to normal position.

In witness whereof, I have hereunto affixed my signature.

JESSE I. ANDERSON.
